UNITED STATES PATENT OFFICE.

GEORGE CORNELIUS CLEMENT, OF BALTIMORE, MARYLAND, ASSIGNOR TO THE BALTIMORE SALESBOOK COMPANY, OF BALTIMORE, MARYLAND, A CORPORATION OF MARYLAND.

COMBINED PAD OR LEAF HOLDING AND LOCKING DEVICE FOR MANIFOLDING SALES BOOKS.

Application filed March 27, 1923. Serial No. 628,020.

To all whom it may concern:

Be it known that GEORGE CORNELIUS CLEMENT, citizen of the United States of America, residing at Baltimore, in the State 5 of Maryland, has invented certain new and useful Improvements in Combined Pad or Leaf Holding and Locking Devices for Manifolding Sales Books, of which the following is a specification.

10 This invention relates to improvements in a combined pad or leaf holding and locking device for manifolding sales books.

It is well known to those skilled in the art 15 in the use of manifolding sales books, that difficulties are encountered in providing a holding means that will hold a pad of tissue sheets, a carbon sheet, or the like, in a pre-determined position with respect to another pad of leaves for the purpose of making 20 duplicate or triplicate copies of a memorandum.

Many of the conventional types of holding 25 devices for manifolding sales books, including the type shown in the drawings, which is in common use and to which the present invention is applied, do not hold and maintain the tissue pad or the like in a locked and an immovable pre-determined position, the resultant being to loosen and 30 disarrange the tissue pad, carbon sheet or the like from the holding device and change its relation with respect to its proper alinement and position with a pad of leaves that are used in combination therewith for making 35 a plurality of copies of the memorandum, thereby affecting the uniformity of the arrangement of the leaves and rapid and efficient use or operation of the sales book.

The clamping members of the holding 40 device shown in the drawing, which is in common use, are liable to become disengaged or disconnected, permitting the resilient movable clamping member to open, thereby allowing the tissue book, carbon paper or the like, to loosen in the holding device to become 45 disarranged, mutilated, torn, or permitted to move out of alinement with its companion or co-operating pad.

The constant locking and unlocking of the 50 clamping member of the conventional type of holding device shown in the drawing weakens the movable clamping member at the point of its connection to its comple-

mentary stationary clamping member, permitting it to sag down and become disconnected from its engagement with the stationary clamping member and to spring away from its clamping position against the cover of the tissue pad, carbon sheet or the like, or the clamping member may become disconnected from the complementary stationary clamping member because of defective construction or workmanship of the means of connecting the movable clamping member and stationary clamping member 65 together for the purpose intended.

The clamping member oftentimes becomes disconnected when the book is roughly used or handled, as for instance, by throwing the book down heavily on a counter or the like, the jar or impact of the book on the counter causes the clamping member to become disengaged from its stationary complementary clamping member, thereby permitting the book to loosen from the holding 75 device.

The primary object of the present invention is to provide a locking means that will lock the clamping members of the holding device together and to prevent the parts 80 from becoming disarranged from each other or from their clamping position with respect to the cover of a pad of tissue sheets, carbon sheet or the like, so that in case of rough usage in handling same or jarring the book, 85 the parts of the holding device will be maintained and locked in their pre-determined clamping position at all times notwithstanding such jarring or rough handling of the sales book.

These and other objects are attained by the mechanism described in the specification and claims and illustrated in the accompanying drawings in which:

Fig. 1 shows a plan view in open position 95 of a conventional type of a cover for a side opening triplicate sales book, having a conventional type of holding device secured thereto and the present invention applied to said holding device.

Fig. 2 is a longitudinal section of a part 100 of the cover of the book showing a holding device and invention applied thereto, taken on the line 1—1 of Fig. 1.

Fig. 3 is an enlarged cross section of an 105 assembled triplicate sales book showing a

tissue pad held by the holding device in co-operative relation with a pad of duplicate and original leaves or the like.

Fig. 4 is a plan view of the holding device showing the invention applied thereto with the clamping member of the holding device in open position and the locking mechanism of the present invention engaging with the stationary complementary clamping bar.

10 Fig. 5 is a plan view of the holding device showing the invention applied thereto with the locking mechanism of the present invention shown in a position preparatory to locking the movable clamping member to the 15 stationary clamping member after connecting the clamping members together.

Fig. 6 is a plan view of the holding device showing the locked mechanism locking the movable clamping member in juxtaposition, 20 parallel with and in alined relation to the stationary complementary clamping member.

Fig. 7 is a side elevation partly in section of the holding device.

25 Fig. 8 is a cross sectional side elevation of a detail of the holding device.

Fig. 9 is a cross sectional side elevation of the holding device taken on the line 6-6 of Fig. 6.

30 Figs. 10 and 11 show an edge and perspective view of a modified form of clamping members and the means of connecting the members to each other.

Figs. 12 and 13 show an edge and perspective view of another modified form of the clamping members and a means of connecting the members to each other.

Fig. 14 shows a detailed view of Fig. 13 in side elevation.

40 Fig. 15 shows a view of one of the pads.

Fig. 16 shows a modified form of holding device.

Fig. 17 shows another form of holding device.

45 The application of the present invention is shown in the drawings as applied to a conventional type of clamping holding device which is applied to a conventional type of side opening triplicate salesbook.

50 Referring to Figs. 1 to 9 the construction is as follows:

The cover of the triplicate salesbook is preferably made in three parts, which are indicated by reference numerals 1, 2 and 3 and preferably hinged together by flexible hinges 4 and 5, made of cloth or the like.

55 One part, 6, of a conventional type of holding device is preferably secured adjacent to and parallel with the edge of the central part 2, of the cover by eyelets 7, or in any other well known manner.

60 The part 6 comprises an angle iron section and is preferably attached to the part 3 of the cover in such a manner as to leave the other section 8 extending upwardly.

The vertically extending section 8 of the angle iron member provides a stationary clamping member for the holding device. A portion of one end of the side 8 is turned at right angles to the body portion forming an ear 9, which is provided with an undercut notch 10 in the lower portion thereof.

65 A movable clamping member 11, has one end turned upon itself to form a loop 12 for engagement with the side and end 8 of the angle iron member. The movable member 11 is attached to the side 8 of the angle member by any well known fastening means.

70 The resilient movable clamping member is made of the same width as the side 8 of the angle iron member and arranged to have the upper edges of the movable member 11 and section 8 of the angle iron member on a plane with each other. The movable member 11 is normally positioned in open position under tension at its free end in a diverging relation to section 8 of the angle member. It is also positioned under tension to extend slightly above the top edge of the side 8 so as to leave its free end inclined therefrom to the point of its connection to the opposite end of the angle iron section 8.

75 Adjacent to the free end of the movable clamping member an uppercut notch 13 is formed. A portion of the end of the movable clamping member contiguous with the notch formed in the movable member is turned at right angles with the body portion of the movable clamping member to provide a finger receiving member 14, to permit pressure to be exerted thereon to manipulate the movable clamping member and force it in parallel relation to the section 8 of the angle bar, in a downward direction to permit it to connect with the stationary clamping member.

80 When it is desired to clamp a tissue pad, carbon sheet or the like to section 8 of the angle iron member, pressure is exerted by the finger or thumb upon the turned portion 14, of the movable clamping member in a downward direction and the tension of the movable member is counteracted and the movable member moved to a position parallel with section 8 of the angle iron member and the notch 13 formed in the movable member 11, engages the notch 10 formed in the ear 9, holding the clamping member in close frictional contact with each other under tension.

85 It will be understood that prior to connecting the movable clamping member to section 8 of the angle iron member forming the stationary clamping member, the cover of tissue pad, carbon sheet or the like, has been first interposed between the clamping members.

90 In Figs. 10 and 11 a modification of the construction of the clamping means is shown with respect to the connection of the clamp-

ing members is shown which consists in connecting the yielding or movable clamping member 11 to the section 8 (or stationary clamping member), together for yielding movement by a coiled flat spring member 24 a portion of which presses against a roller 25. The roller is rotatably mounted on a pin 26 which in turn is journaled in the ears 27 and 28 which are preferably made integral with section 8. In Figs. 12, 13, and 14 another modification is shown of the means of yielding connecting the movable member 11 to section 8, that is, a clip 29 is provided to fit over section 8 (stationary clamping member). A roller 30 is rotatably mounted upon a pin 31. One end of the movable clamping member 11 is inserted between the roller 30 and section 8 under tension. It is also attached thereto. The clip 29 and the roller are positioned with respect to the movable member 11 so as to produce a tension in the movable member to normally hold the movable clamping member 11 in open position as shown in Figs. 12 and 13. The above describes the conventional means of holding the cover of the tissue book, carbon sheet or the like in a pre-determined relation with reference to a pad of duplicate and original leaves or the like and while the parts are engaged with each other clamping the tissue book therebetween. The tissue book is held in proper alignment or relation with another pad or the like, used in combination therewith for the purpose intended.

In order to prevent the movable clamping member from becoming disengaged from its clamping position with respect to the cover of the tissue pad, carbon sheet, leaf, or the like, the present invention provides a locking mechanism which maintains the movable member when connected in parallel relation to the side 8 or stationary clamping member of the holding device and its top edge on a plane therewith which prevents the movable clamping member from moving in a vertical direction whether or not its connection to section 8 of the angle member has become weakened or has become disengaged from other causes.

The locking mechanism of the present invention comprises a yielding resilient member 15, which is attached to section 8 of the angle iron member by rivets 16 or the like.

The body portion at 17 and 18 is bent or curved to permit the yielding means to yield more readily under pressure. The free end 19 of the yielding member 15 extends outward, forward and beyond the end of the section 8 of the angle iron member to provide a finger contacting means for counter-acting the tension of the yielding member and forcing it to unlocked position as shown in Fig. 5.

A pin 20, is secured to the end of the

yielding member 15, which is adapted to normally extend through a suitable opening provided in section 8 of the angle iron member and an opening aligned therewith formed in the movable clamping member 11, thereby engaging locking, holding, supporting and maintaining section 8 of the angle iron member forming the stationary clamping member on a plane with the movable clamping member. The locking pin 20 when so engaged constantly maintains the clamping member in locked position with respect to section 8 and prevents the disengagement or separation of the movable clamping member from section 8.

In the modified form shown in Fig. 16 a flat spring 32 is attached to the holder to constantly exert a pressure against the clamping member 11 to yieldingly hold the member 11 in locked position. The spring 33 shown in Fig. 17 is pressed from the holder and exerts a pressure against the bar 11 to hold the member in locked position.

The application of the holding means and locking device is shown applied to a conventional type of triplicate sales book. (See Fig. 3.)

Reference numeral 21 represents a pad of duplicate and original leaves, 22 a pad of tissue sheets which are preferably attached to a cover 23. A double faced carbon sheet or the like is indicated by reference numerals 21'.

The used leaves 24 or the tissue pad are shown deposited underneath the part 3 of the cover. It will be understood by those skilled in the art, that when it is desired to make triplicate copies using the arrangement shown in Fig. 3, the one of the leaves of the tissue pad 22 is placed between the original and duplicate sheets and a double faced carbon sheet is interposed between the tissue sheet and the original. When the memorandum is indorsed, on the original it is transmitted through the medium of the carbon sheet making appropriate copies of the inscription.

When such memorandum as desired is indorsed thereon, the part 3 is turned or swung to the left, allowing the used sheet to fall upon the part 2 of the cover or in juxtaposition with the other used tissue leaves as shown in Fig. 3.

The part 3 of the cover is then turned or swung to the left in the position as shown in Fig. 3, preparatory to being manipulated for producing another series of triplicate memorandum.

Referring to the figures of the drawing, commencing with Fig. 4, the operation in brief is as follows:

The holding and locking means are normally in the position shown in Fig. 4. When it is desired to clamp, hold and lock a cover of a tissue pad, carbon sheet or the like, the

cover is placed over the top of section 8 of the angle iron member as shown in Fig. 3.

The locking member 15, is then forced to the position shown in Fig. 5, the movable number 11 is then forced into an engagement with the notched portion 10, formed in the ear 9 of the section 8, thereby clamping and holding the cover of the tissue book, carbon sheet or the like in an appropriate position 10 with respect to the pad or the like.

The locking member 15 is then released and the pin 26 carried thereby automatically engages the alined apertures provided in section 8 of the stationary clamping member 15 and movable member 11, as shown in Fig. 6. The pin 20 extends through both parts of the clamping members and locks same together.

The movable clamping member is manipulated for engagement or disengagement with section 8 of the angle iron member by a pressure exerted upon the finger member 14 as shown in Figs. 5 and 6.

When it is desired to remove the book from the yielding clamping device, the locking member is forced under tension downward, permitting the movable clamping member 11 to become disengaged from the notch 10 in the ear 9 of section 8.

When the movable clamping member is released, it automatically returns to its normal open position, as shown in Fig. 4, permitting the tissue pad, carbon sheet or the like, to be removed with efficiency and convenience and a new one inserted, if desired.

The combined holding and clamping device and means of locking the clamping device in its clamping position with respect to the cover of the tissue pad, carbon sheet 40 or the like is shown in the drawings as applied to a conventional type of side opening triplicate sales book which is the referred embodiment of the application of the invention for the purpose intended.

It is not intended to limit the invention to the application shown, as it can be applied for use with duplicate, triplicate salesbooks with end and side openings, of different types. And also in holding a carbon sheet or leaves of the books used for other purposes without departing from the spirit or principle involved in the invention,

The claims appended hereto, therefore, are not intended to be limited in scope to a combined holding means and locking device as applied to any particular type of sales book or the like, but are drawn to cover in a generic sense, other methods or means for making a plurality of copies of memorandum where the combined holding and locking device of the type shown is required or desirable for use.

I claim:

1. In a holding and locking device for use 65 in association with manifolding sales books

comprising a tissue pad and cover therefor, an angle iron member attached to the cover, a movable tensioned clamping member which is attached to the upright section of the angle member at one end, means 70 integral with the clamping member and upright section of the angle iron member to hold the movable member in juxtaposition to the upright section of the angle iron member and a separate locking means to 75 prevent the movable clamping member from becoming disengaged from its clamping position or from moving in vertical directions with respect to the upright section of the angle member, thereby yielding 80 locking the connected clamping members together.

2. In a holding device for manifolding sales books comprising an angle iron, one section of which is adapted to form one part 85 of a clamping member, a movable clamping member attached thereto and diverging therefrom under tension, means to connect said members together in juxtaposition to each other and a yielding locking member 90 secured to the angle iron and provided with a pin on its free end which is adapted to enter suitable apertures in the movable member and a section of the angle iron member to prevent movement of either with 95 respect to each other, as and for the purpose described.

3. In a holder, a member having an ear formed on one end and provided with a notched portion, a second resilient member 100 fastened to said first mentioned member at one end and adapted to engage a notch formed in the ear of the first mentioned member at its free end and a separate locking means attached to the first mentioned 105 member to lock the members together at one end.

4. In a clamp holding device for manifolding salesbooks, a cover made of a plurality of parts, a stationary angle iron 110 member secured to one part of the cover, a yielding and resilient clamping member secured to the stationary angle iron member in such a manner as to normally diverge therefrom under tension, means to connect 115 the free end of the diverging clamping bar in juxtaposition to the upright leaf of the angle iron member, and a separate locking means to engage both members.

5. A book clamping device including 120 companion clamping members having a separating spring action when free, means for holding the members in clamping co-operation against such spring action, and means for connecting the members to insure 125 the security of said holding means.

6. A book clamping device including members connected at one end and having 130 an inherent separating action when free at the opposite or free ends, means for inter-

fitting said members at the free ends to holding said members in clamping cooperation, and means for preventing disconnection of the interfit.

5 7. A clamping device including members connected at one end and having an inherent separating action when free at their ends, said members being formed at their free ends to interfit through a relative

10 predetermined movement to hold said members in clamping cooperation, and means for preventing such relative movement of the free ends of said members as will permit a separation of such interfit.

15 8. A clamping device comprising bars connected at one end and normally spaced at their free ends, the free ends of such bars being formed for interlocking cooperation to hold the bars in clamping relation, and means to prevent casual interruption of the

20 interlocking cooperation.

9. A clamping device comprising bars having a separating action when free, the free end of one of said bars being formed with a notch and the free end of the other 25 of said bars being formed with a projection to seat in said notch to hold the bars in clamping cooperation, and means to prevent casual separation of such projection and notch.

30 10. A clamping device comprising bars connected at one end and free at the opposite ends, the bars having a normal tendency to maintain their free ends spaced apart, said bars being formed at their free 35 ends for a cooperating interfit to hold the bars in clamping relation throughout their lengths, and means engaging both bars to prevent casual separation of such interfit.

In testimony whereof I affix my signature.

GEORGE CORNELIUS CLEMENT.
